CRACKING APPARATUS AND METHOD OF
OPERATING THE SAMEDonald L. Jacobs and Eddie M. Dons, Tulsa, Okla.,
assignors to Mid-Continent Petroleum Corporation,
Tulsa, Okla., a corporation of Delaware

Application October 10, 1932, Serial No. 637,014

3 Claims. (Cl. 196—47)

This invention relates to cracking apparatus and methods of operating the same, and more particularly to the conversion of high boiling point hydrocarbons into low boiling point fractions. One of the objects of the invention is to produce a highly efficient system of this kind wherein the several elements of the system cooperate with each other to establish and maintain all of the varying conditions of pressure and temperature at a relatively low cost.

10 A further object is to subject the hydrocarbons to the desired pressures in a cracking zone and reflux condenser, and to accomplish this in a feasible and economical manner, while subjecting the cracked vapors to a combination of conditions whereby they are effectively utilized to increase the efficiency of the cracking system, without in any way impairing the functions of the reflux condenser.

15 With the foregoing and other objects in view, the invention comprises the novel method, construction, combination and arrangement of parts hereinafter more specifically described and illustrated in the accompanying drawing, wherein is shown the preferred embodiment of the invention. However, it is to be understood that the invention comprehends changes, variations and modifications which come within the scope of the claims hereunto appended.

20 In the preferred form of the invention, a stream of hydrocarbons is conducted through a cracking zone where it is subjected to the desired heat and pressure, the cracked mixture being transmitted into a separating chamber where the vapors separate from the residuum and pass into a reflux condenser. The vapors are cooled while under pressure in the reflux condenser, to condense the high boiling point fractions and return them under pressure to the cracking zone. The 25 low boiling point vapors pass from the reflux condenser under pressure, and thence through a turbine, or other fluid-actuated power plant, where their pressure is converted into mechanical energy.

30 Since the readily condensable vapors are condensed in the reflux condenser, without passing into the power plant which receives the low boiling point vapors, it will be understood that the vapors entering the power plant are clean and free of the more readily condensable fractions. A 35 relatively simple turbine can, therefore, be employed to convert the waste energy into mechanical power.

35 As a further step to eliminate, or reduce, the condensation in the power plant, the cooled va-

pors passing from the reflux condenser are preferably superheated before they enter the power plant, and we have shown how this may be accomplished without any additional cost in the operation of the cracking system.

40 The specific combination and arrangement of elements herein disclosed enable all of these results to be accomplished in a simple manner, and the several elements cooperate with each other to provide the high efficiency while maintaining the desired conditions in each element of the cracking system.

The drawing is a diagrammatical view of a cracking system embodying the features of this invention.

45 1 designates a furnace containing a cracking coil 2 wherein a stream of hydrocarbons is heated to a cracking temperature while subjected to pressure transmitted from a pump 3 which forces the stream into the cracking coil.

The cracked mixture discharged from the coil 2 is conducted into a separating chamber 4 where the residuum is discharged through a pipe 5 provided with a valve 6 to regulate the flow while maintaining the contents of the separating chamber under pressure.

50 The residual oil and carbonaceous material are thus separated from the vapors which pass from the separating chamber through a pipe 7 extending into a reflux condenser 8 where the vapors are cooled to condense the high boiling point fractions. The reflux condensate falls to the bottom of the condenser 8, while the low boiling point fraction in the form of vapors is discharged through a pipe 9 at the top of the reflux condenser and conducted to a final condenser 10, as will be hereafter described.

55 The fresh charging stock, such as gas oil, or other heavy hydrocarbon liquid, may be forced into the reflux condenser through a pipe 10', so as to commingle with hot vapors and reflux condensate. The cool charging stock is thus pre-heated, and a mixture of the hot reflux condensate and charging stock collects in a pool at the bottom of the reflux condenser. A pipe 11 extends from this pool to the inlet of the pump 3, and a pipe 12 connects the outlet of the pump to the inlet of the cracking coil 2.

60 As an example of operating conditions desirable for intense cracking, we will now set forth a specific example, but it is to be understood that the invention is not limited to the details of this illustrative example.

65 The mixture of reflux condensate and charging stock may be delivered to the pump 3 under a

pressure of about 200 pounds per square inch and under a temperature of about 750° F. The pressure of the pump may be great enough to discharge the hot mixture to the inlet of the 5 cracking coil 2 under a pressure of about 300 pounds per square inch, or any other desired high degree of pressure.

The mixture to be cracked will thus be subjected to a high pressure in the cracking coil, and 10 the temperature of the stream may be increased from about 750° F. at the pump 3 to about 875° F. at the discharge end of the coil.

The contents of the separating chamber 4 may 15 be maintained at a temperature slightly lower than 875° F. and under a pressure of about 200 pounds per square inch to permit separation of the vapors from the residual material. This pressure is continued through the reflux condenser to a power plant 13 where the pressure is 20 reduced to maintain the final condenser 10 under about atmospheric pressure.

The cracked product is thus condensed at 25 atmospheric pressure, while the reflux condenser and separating chamber are maintained under any desired higher pressures. The mixture of reflux condensate and charging stock is discharged from the reflux condenser and conducted through the pipe 11 under the pressure maintained in the reflux condenser.

30 The power plant 13 is preferably a fluid-actuated turbine having an inlet pipe 14 connected to a superheater 15, and a discharge pipe 16 connected to the final condenser 10. A by-pass 17 connects the pipe 14 to the pipe 16, as shown in 35 the drawing, so that the vapors can be discharged to the final condenser, without passing through the power plant. The pipes 14, 16 and 17 are provided with valves 18, 19 and 20, and an additional valve 21 may be interposed between 40 the final condenser and the discharge end of the by-pass 17.

The superheater 15 comprises a chamber interposed between the pipes 9 and 14 to receive 45 the cooled vapors passing from the reflux condenser 8 to the power plant 13. As a diagrammatical illustration of a means for indirectly transmitting heat to these vapors we have shown a coil 22 located in the superheater and having its discharge end connected to a condenser 23.

50 Relatively hot vapors are conducted to the coil 22 by means of a pipe 24, and these hot vapors may be obtained from another part of the system. To illustrate this feature, we have shown an evaporating chamber 25 connected to the 55 residuum pipe 5 and also connected to the vapor pipe 24. The pressure-reducing valve 6 in the pipe 5 is regulated to maintain the desired high pressure in the separating chamber 4 while the evaporator 25 is maintained under a pressure 60 only slightly above atmospheric pressure. In response to this reduction of pressure, the volatile constituents of the highly heated residuum are vaporized, and the hot vapors pass through the pipe 24 to the superheating coil 22, and thence to 65 the condenser 23. The temperature of these hot vapors will be relatively high, for example, about 750° F. The cooled vapors leaving the reflux condenser at a temperature of, for example, 460° F., are, therefore, superheated to effectively 70 transmit energy to the power plant 13, without undue condensation which would otherwise result from the work performed and the reduction of pressure at the power plant.

75 During the normal operation of the system, the valve 19 in the by-pass 17 may be closed, while

the valves in the pipes 14 and 16 are open. The power plant 13 will then be operated by the superheated vapors.

In starting the system, the valves 18 and 20 in the pipes 14 and 16 are preferably closed, while 5 the valve 19 in the by-pass is open, and the valve 21 in the vapor line is also open. Cool charging stock may be admitted through the pipe 10' at 10 the reflux condenser and conducted therefrom through the pipe 11 to the pump 3, said pump being operated from any suitable source of power 15 to force the charging stock in an endless course through the heating coil 2, and into the separating chamber 4 from which it returns to the pump by passing through a pipe 26 leading to the pipe 11. The circulation in this endless course results in a gradual heating of the charging stock, the air and water vapors being expelled through the valve 19 in the by-pass 17 leading to the final condenser 10.

20 Thereafter, as the temperature and flow of vapor increases, the valve 19 is adjusted to gradually increase the pressure and establish the normal operating conditions. When the required pressure and velocity is obtained in the by-pass 17, its valve 19 is closed, and the valves 18, 20 and 21 in the pipes 14 and 16 are opened to start the power plant 13. The admission of charging stock through the pipe 10' is continued, the valve 27 in the return pipe 26 is closed, and the residuum valve 6 is opened during the normal running conditions. After these conditions are established, mechanical power is produced at the power plant 13, and such power may be employed for any desired purpose. For example, a portion 30 of this power may be transmitted through a clutch 28 to a pump 29 which forces the charging stock into the system.

To maintain the predetermined degree of pressure in the reflux condenser 8 when the conditions in the power plant 13 would permit a relatively free escape of vapor, the valves 18 and 20 40 may be selectively adjusted to provide the desired conditions, and whenever necessary or desirable, the valve 19 in the by-pass can be regulated to 45 divert a portion of the vapors from the power plant.

We claim:

1. In the art of cracking hydrocarbon oils, the method which comprises cracking and vaporizing 50 a hydrocarbon oil under pressure, cooling the resultant cracked fluid under pressure to condense the fractions having relatively high boiling points, indirectly superheating the remaining vapors by transmitting heat from the 55 resultant cracked fluid formed during the cracking operation, reducing the pressure of the superheated vapors while transmitting them through a fluid-actuated power plant to convert the vapor pressure into mechanical energy, and 60 condensing the vapors discharged from said power plant.

2. In the art of cracking hydrocarbons, the method which comprises conducting a stream of hydrocarbon oil through a cracking zone where 65 the oil is subjected to a cracking operation under pressure, transmitting the cracked mixture into a separating chamber where the vapors while under pressure separate from the hot residuum, withdrawing residuum from said chamber and 70 reducing the pressure on said withdrawn residuum to vaporize its volatile constituents, conducting vapors from said separating chamber and cooling them under pressure to condense the fractions having relatively high boiling 75

points, indirectly transmitting heat from said volatile constituents to the cracked vapors not condensed during said cooling operation while preventing a mixture of said volatile constituents 5 and cracked vapors, so as to superheat said cracked vapors, reducing the pressure of said superheated cracked vapors while transmitting them through a fluid-actuated power plant to convert a substantial portion of the pressure into 10 mechanical energy, and condensing the vapors discharged from said power plant.

3. In an apparatus for cracking hydrocarbons, a cracking means wherein a stream of the hydrocarbons is subjected to a cracking temperature, a final condenser wherein the cracked product is condensed, a reflux condenser between said cracking means and final condenser, a separating chamber interposed between said reflux condenser and cracking means to separate the 15 residuum from the vapors, an evaporator connected to said separating chamber to receive the hot residuum, a pressure-reducing valve inter-

posed between said evaporator and separating chamber to permit free vaporization of the volatile constituents of the hot residuum, a pump connected to the inlet of said cracking means to provide a high pressure therein, means for conducting reflux condensate and charging stock to said pump to maintain said high pressure, a power plant to maintain the desired pressure in the reflux condenser, said power plant being interposed between said reflux condenser and final 10 condenser to obstruct the cracked vapors passing from said reflux condenser while converting their pressure into mechanical energy, a superheater interposed between said reflux condenser and final condenser to superheat the cooled 15 vapors before they enter said power plant, and a vapor conductor connecting said evaporator to said superheater so as to transmit heat from the vaporized constituents of the residuum to the cooled vapors passing from said reflux condenser. 20
